CLAIM

The ornamental design for a pick holder as shown and described.

DESCRIPTION

FIG. 1 is a top front right perspective view of a pick holder, showing my new design;

FIG. 2 is a bottom rear left perspective top rear left view thereof;

FIG. 3 is a front elevation view thereof, wherein the rear elevation view is an identical image thereof;

FIG. 4 is a left elevation view thereof, wherein the right elevation view is an identical image thereof;

FIG. 5 is a top plan view thereof; and,

FIG. 6 is a bottom plan view thereof.
